UNITED STATES PATENT OFFICE

HAROLD H. DUTTON, OF WASHINGTON, DISTRICT OF COLUMBIA

LEWIS

Application filed June 14, 1926. Serial No. 115,894.

This invention relates to a lewis designed for use in a single hole drilled in the center of the top of the stone in place of the two hole pin type lewises or other hoisting means which require more preparation and inconvenience in their employment.

The object of the invention is to provide a lewis which may be generally inserted into and removed from a single hole formed in the top of the stone, and one which will be automatically tightened under the action of the weight of the stone itself, the construction being such that an increasing pull on the lifting ring will cause an increasingly higher pressure of the sides of the device against the walls of the hole so that the possibility of slippage or dropping the stone is entirely eliminated, and further so to construct the lewis that it may contain within itself the means necessary for its immediate release from the stone into which it is inserted after the said stone has been hoisted into place.

The invention also consists in the novel features of construction and combinations of parts hereinafter set forth, pointed out in the claims, and set forth in the accompanying drawings forming a part of this specification and in which:

30 Fig. 1 is a vertical elevation of the device, the parts being shown in the unexpanded position ready for insertion in the stone, the position of the lifting ring when used as a hammer being indicated by dotted lines,

35 Fig. 2 is a vertical elevation and partial section showing the arrangement of the parts when the lewis is inserted in the hole in the stone but prior to the lift being made,

40 Fig. 3 is a vertical section thru the sleeve and expander nut showing the positions of the several pieces when the lewis has been tightened and is ready to lift the stone, and

45 Fig. 4 is a sectional view on the line 4—4, of Fig. 1 looking in the direction of the arrows.

In the drawings, the lewis comprises a slidable slotted sleeve, designated generally 1, thru which passes a rod 2, to the lower end of which is attached an expander nut 3, of conical shape, the upper end of the rod 2 be-

ing fashioned into a loop or eye 4 thru which passes a lifting ring 5, preferably of the shape shown, which is freely movable in the loop 4. The sleeve 1 consists of a solid piece of metal, preferably grooved as shown at 6 to afford a better grip for the hands of the operator, bored out to allow the insertion of the rod 2 and reduced in section to its lower part to form the expandable leaves 7 by being slotted by a plurality of cuts 8. The leaves 7 are tapered on their inner surfaces as shown at 9, the particular degree of slope chosen being one of the important features of the device, as will be shown later. On the exterior of the leaves 7 at the lower end is formed a circumferential projection or ridge 10, one being shown here, although a plurality of the same may well be employed. This ridge or projection is made a certain size corresponding to the diameter of the hole intended to be drilled in the stone, the purpose of this appearing later. The sleeve 1 is freely movable vertically on the rod 2 within convenient limits, depending on the desired dimension of the parts with the restriction that it must be capable of entire separation from the expander nut 3.

The rod 2 has its lower end threaded or otherwise arranged to make possible the attachment of the expander nut 3. This nut 3 is of conical shape as shown, the inclination of the sides being suitably chosen with respect to the taper of the leaves 7 in accordance with an important feature of this device to be later described.

In use the lewis is inserted in a hole drilled in the center of the top of the stone to be lifted, it then being positioned as in Fig. 2, the projection or ridge 10 now being in contact with the sides of the hole and the rod 2 held up by the ring 5 at the top of the loop 4 so that the expander nut 3 is just entered within the leaves 7. By holding the sleeve 1 with one hand and pulling upward on the ring 5 with the other hand with a horizontal twisting motion the operator will cause the leaves 7 to be forced outwardly by the further introduction of the nut 3 into the sleeve 1 and the ridge 10 will either press increasing firmly against the side walls of

the hole, or may be actually forced into the stone if it be relatively soft. The lewis will then appear as in Fig. 3 and the lift may now be made by the hook of the hoisting tackle engaging the ring 5 and drawing it upward, it being easily seen that the greater the pull on the ring 5 thru the tackle, the more tightly will the nut 3 wedge itself between the leaves 7 and there exert more and more pressure against the sides of the holes and thus further assure the positive holding action of the device.

Now, in order that the leaves 7 may not be bent or otherwise distended when spread apart thru the entrance of the expander nut 3, by reason of the latter engaging the inner wall 9 at one point only, I have provided a certain slope on the interior of the leaves as shown at 9 and a slightly divergent slope 20 for the sides of the nut 3 based on calculated observations of the relative positions of the parts 3 and 7 when under load, the different inclinations of the two faces making possible the exact coincidence and extended contact of the interior face 9 of the sleeve 7 and the sides of the nut 3 when in the expanded condition. This exact coincidence of the contacting surface will provide adequate extended contact between the parts under all 25 conditions of lifting whether small or large loads are to be handled, thus providing against distortion or injury to the lewis when in use.

In practical work it has been found desirable to have a 2° taper on the internal surface of the sleeve 9 and a 3° taper on the surface of the expander nut 3, these particular proportions accomplishing the intended purpose of providing the extended contact between the 30 internal surface of the sleeve 9 and the expander nut 3. It is conceivable that other sets of tapers might well be employed, the above mentioned figures merely being noted as one practical combination.

Having moved the stone to its required position and the tackle being unhooked, the lewis may be instantly removed by using the lifter ring 5 as a hammer to tap upon the lower end of the loop 4 in the rod 2, thereby causing the expander nut 3 to loose itself from the leaves 7 which will then return to their normal position and allow the sleeve to be removed from the hole. Thus, in addition to the novel means by which the lifting itself is accomplished, I have also incorporated an arrangement of parts which eliminates the necessary of employing a hammer or other tool to remove the lewis after use.

While I have illustrated and described one 40 preferred form of my invention, it will be evident that numerous variations in form and proportions may be made without departing from the scope of the invention as defined in the following claims. Thus the ridge or rib 10 may be either continuous or

interrupted and the complementary faces of the leaves and expander nut may have a cross-sectional form other than the circular form shown in Fig. 4. As above indicated the slopes given these faces may be increased where found desirable so long as the degree of displacement of the leaves in the gripping operation serves to bring the inner surfaces of the leaves into extended contact with the expander nut. Thus there is obtained both freedom from distorting the leaves and at the same time an increase of pressure applied by the expander nut over a considerable area but localized in the rib 10 when applied to the stone to be lifted.

What I claim as new and desire to secure by Letters Patent of the United States is as follows:

1. In a lewis, a rod, a conical expander nut on one end and a loop on the other end of said rod, a sleeve slidable on the rod, said sleeve being slotted at one end and having an internal taper in extended contact with the conical expander nut, and a ring held in said loop, said ring being movable longitudinally 55 of the loop into striking engagement with either end thereof.

2. In a lewis, a rod having an elongated eye formed at one end, an expander nut thereon, a sleeve slidable on the rod, said sleeve being slotted at one end and having an internal taper in extended contact with the expander nut, an outer engaging means consisting of a circumferential ridge, and a lifting ring in the eye on said rod.

3. In a lewis, a rod, a tapering nut thereon, a sleeve slidable on the rod and over the nut, said sleeve being slotted at one end, the said end having a taper slightly less than that of the nut.

4. In a lewis, a rod, an expander nut thereon, an expansible sleeve carried on the rod and slidable over the nut, lifting means loosely carried by the rod and movable longitudinally with respect to the rod to cause the nut to travel out of the sleeve.

5. In a lewis, a rod, a tapering nut thereon, a sleeve slidable on the rod and over the nut, said sleeve being expansible at one end, the said end having a taper slightly less than that of the nut and a relatively narrow outer engaging ridge.

6. In a lewis, a rod, a tapering nut thereon, an expansible sleeve, slidable on the rod and over the nut, and the sleeve having an internal taper sufficiently less than that of the nut to bring their opposing surfaces into extended coincidence when the sleeve is expanded over the nut.

In witness whereof I have hereunto affixed my signature.

HAROLD H. DUTTON.
